UNITED STATES PATENT OFFICE.

JONAS AUGUST LARSON AND ERIC JOHNSON, OF CHICAGO, ILLINOIS.

ROTARY ENGINE.

Application filed April 10, 1922. Serial No. 551,221.

To all whom it may concern:

Be it known that we, JONAS AUGUST LARSON and ERIC JOHNSON, both citizens of the United States, and residents of Chicago, 5 in the county of Cook and State of Illinois, have invented a new and useful Improvement in Rotary Engines, of which the following is a full, clear, and exact description.

Our invention relates to improvements in 10 rotary engines, and it consists in the combinations, constructions, and arrangements herein described and claimed.

An object of our invention is to provide 15 a rotary engine of the type described which may be driven by steam, compressed air, or water.

A further object of our invention is to 20 provide a rotary engine of the character described in which the blades, when not actually in use, are retracted within the body of the rotor.

A further object of our invention is to 25 provide a rotary engine of the character described which may be operated at low speed with a minimum loss in efficiency.

A further object of our invention is to 30 provide a rotary engine of the character described which is simple in construction, which may be manufactured cheaply, and which is thoroughly practical for the purpose intended.

Other objects and advantages will appear 35 in the following specification, and the novel features of the invention will be particularly pointed out in the appended claims.

Our invention is illustrated in the accompanying drawings, forming part of this application, in which—

Figure 1 is a sectional view of an embodiment of my invention, and

Figure 2 is a sectional view along the line 2—2 of Figure 1.

In carrying out our invention, we make use of a base 1 having an upright stator 2. 45 The stator 2 comprises an upwardly extending arcuate surfaced member 3 having flat vertical sides 4 and 5. An inlet nozzle 6 is supported adjacent one end of the stator 2 and an arcuate shoe 7 is supported on the 50 stator 2 and arranged to extend upwardly from the nozzle 6 to a point adjacent the opposite end of the stator 2.

A rotor 8 is provided and is comprised, 55 namely, of two circular core portions 9 and 10. The cores 9 and 10 are fitted to one another by means of dowel pins 11, which

are received in holes 12, provided in one of the cores. Each of the cores 9 and 10 is provided with a band 13 tightly fitted upon the periphery of the outer surface thereof. A 60 narrow notch 14 in the inner sides of the cores 9 and 10 adjacent the bands 13, provides means for the entrance of the arcuate shoe 7, as shown in the drawing.

Means for rotatably mounting the rotor 65 8 in operative engagement with the stator 2 is provided in a pair of stub shafts 15. The shafts 15 are centrally mounted on the cores 9 and 10 comprising the rotor 8, by means of plates 16 and rivets 17. The shafts 15 70 are supported in bearing sleeves 18 provided in upright bearing supports 19. The bearing supports 19 are supported upon the base 1 heretofore described.

A pulley wheel 20 is secured upon one of 75 the stub shafts 15 and provides means for driving machinery or the like.

The rotor 8 is provided with an annular groove 21 formed by grooving the cores 9 and 10 adjacent to their inner edges. Each 80 of the cores 9 and 10 are provided with radially extending grooves 23 in which metal blades 24 are slidably disposed. The inner ends 25 of each diametrically opposed pair of blades 24 have disposed therebetween a 85 compression spring 26. The compression spring 26 is mounted concentric a rod 26^a carried by one of the blades 24. The springs thus serve to constantly press the blades 24 90 outwardly.

That end of the stator 2 adjacent the nozzle 6, is provided with a spring band 27, which band is pressed into close engagement with the bottom of the groove 21 in the stator 2, and the opposite end of which is 95 disposed beneath the nozzle 6. The opposite end of the stator 2 is provided with an outwardly extending arcuate surface 28.

The purpose of this surface 28 is to guide the blade 24 as it strikes the stator toward 100 the center of the rotor 8 and upon the arcuate surface 29 of the vertical arcuate surfaced member 3.

It will be noted that the shoe 7 fits snugly between the bands 13 and the notches 14. 105 The tendency of the springs 26 to press the blades 24 outwardly is to also press the shoe 7 in close engagement with the bands 13, thus insuring a tight packing at this point. The outer end 30 of the shoe 7 is at 110 a short distance from the upper end 31 of the arcuate surfaced portion 28 of the

stator 2, and the space therebetween provides an outlet or exhaust port for the engine.

From the foregoing description of the 5 various parts of the device, the operation thereof may be readily understood. Let us assume that the device is to be operated by steam. In this case, the steam feed pipe will be connected to the nozzle 6 and the 10 steam turned on. As the steam enters the nozzle 6, it will be directed upwardly by the band spring member 27, and will fill the space 32 between the blade 24 and the band 27. When the space 32 has been filled 15 with steam and pressure exerted upon the adjacent blade 24, the rotor 8 will turn in a clockwise direction, as viewed in Figure 1. This must occur, since the steam cannot contact the blades 24 below the nozzle 6 20 for the reason that the blades are retracted toward the center of the rotor 8, and secondly, that there is no space for the steam to enter, the arcuate surfaced member 3 being disposed closely adjacent the bottom 25 of the grooves 21.

As the rotor 8 revolves in a clockwise direction, the steam in the space 32 will ultimately be moved to the exhaust port intermediate the end 30 of the shoe 7 in the 30 point 31 of the stator 2. At this point, fresh steam will be driving the blades 24 adjacent the spring band 27. As quickly as the blades 24 move above the band 27 in their clockwise movement, they will be forced out and in 35 close engagement with the shoe 7 by means of the springs 26 pressing upon their inner ends 25. When the blades 24 contact the arcuate surface 28 of the stator 2, they will be retracted in the rotor 8, and will be 40 guided by means of this arcuate surface onto the arcuate surface 29 of the upright member 3. The blades 24 will remain in this retracted condition until they have moved out of engagement with the arcuate surface 29.

The operation of our rotary engine would 45 be precisely the same if compressed air or water was used in place of steam. It will be noted that, since there is no place for the steam to escape, that the blades 24 must be moved forward or in a clockwise direction, 50 and thus the action of our engine in its operation is positive, which of course is unlike the operation of the steam turbin and similarly driven devices.

Means for locking the cores 9 and 10 to 55 one another is provided in threaded machine screws 22 as shown in dotted lines in Figures 1 and 2.

An increase in the diameter of the rotor 8 will of course provide an increase in the 60 leverage of the blades relative to the shafts 15 and thereby increase the horse power of the engine.

We claim:

A device of the character described comprising a rotor having a circular body portion and a concentric groove in the peripheral wall thereof, said rotor having a marginal groove on each of the sidewalls of the concentric groove adjacent the peripheral wall 70 of the rotor, a plurality of spring pressed blades radially disposed in said rotor and arranged to be moved outwardly and transverse to the concentric groove, a stator arranged to partially enter the concentric 75 groove in said rotor and having an arcuate surface contacting said rotor for a portion of its circumference at the base surface of said concentric groove, an arcuate shoe supported by said stator and having its longitudinal edges disposed within the marginal grooves in said rotor, and a nozzle projected through said shoe, whereby steam or the like may be admitted to the concentric groove in said rotor to drive said rotor. 80

JONAS AUGUST LARSON.
ERIC JOHNSON.
